APPARATUS FOR FEEDING POWDERED FUEL

Aubrey J. Grindle, Chicago, Ill., assignor to Gas-koal Corporation, Chicago, Ill., a corporation of Delaware

Application January 9, 1935, Serial No. 997

16 Claims. (Cl. 302—49)

The present invention relates to improvements in apparatus for feeding powdered fuel and adapted for domestic use and other small heating installations.

One of the objects of the invention resides in the provision of a new and improved fuel feeder adapted to supply a mixture of fuel and primary air under pressure to the burner.

Other and more specific objects reside in the provision of a fuel feeder comprising a novel sprocket or gear feed wheel for delivering the fuel from a hopper to the suction of a delivery blower, new and improved means for regulating the supply of fuel and air to the blower, and novel means for agitating the fuel in the hopper to insure an adequate supply of fuel about and to the feed wheel at all times.

Another object is to provide a novel powdered fuel feeder in which the fuel is entrained in a stream of air drawn from the hopper by the blower.

A general object is to provide a new and improved powdered fuel feeding apparatus which is simple, compact and inexpensive in construction, which is reliable and capable of accurate control, and which is not likely to jam or clog in use.

Further objects and advantages will become apparent as the description proceeds.

In the accompanying drawings, Figure 1 is a front elevational view, on a reduced scale, of a combustion apparatus embodying a feeding apparatus having the features of my invention.

Fig. 2 is a vertical sectional view of the combustion apparatus.

Fig. 3 is a fragmentary view, partially in front elevation and partially in vertical section along line 3—3 of Fig. 4, of the fuel feeding apparatus.

Fig. 4 is a fragmentary horizontal view, partially in section along line 4—4 of Fig. 3.

Fig. 5 is a fragmentary vertical sectional view taken along line 5—5 of Figs. 3 and 4.

While the invention is susceptible of various modifications and alternative constructions, I have shown in the drawings and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

Referring more particularly to the drawings, the fuel feeding apparatus, constituting the exemplary embodiment of the invention, is shown with a combustion apparatus comprising gener-

ally a heater 1 having a combustion chamber 2, a fuel burner 3 discharging into the chamber, and power operable means 4 for feeding fuel to the burner.

The various units of the combustion apparatus are conveniently mounted, compactly arranged and substantially enclosed within an outer housing 5 which is rectangular in shape, and which comprises a horizontal base plate 6, upstanding front, rear and end walls 7, 8, 9 and 10, and a top wall 11.

The heater 1 shown comprises an upright cylindrical outer shell 12 having upper and lower end walls 13 and 14, and resting on the base plate 6. A transverse vertical partition wall 15 serves to enclose the heater 1 within a compartment lined with a suitable heat insulating material 17.

The combustion chamber 2 is defined by a plurality of vertically superimposed coaxial sections, namely upper and lower cylindrical inner shells 18 and 19, respectively of relatively small and large diameters, and an intermediate truncated conical section 20. The shell 18 extends through the upper end wall 13 to the wall 11 and, with the shell 12, defines an annular heating chamber 21 for water, steam or hot air, etc. A lining 22 of a suitable refractory material is provided within the shell 18 and the underside of the circumscribed portion of the wall 11. The lower shell 19 extends coaxially in closely peripheral spaced relation to the shell 12 to define an annular water leg 23 opening from the chamber 21. The combustion chamber 2 also has a bottom wall 24 which extends in spaced relation to the lower end wall 14 of the shell 12 to form an inward annular extension 25 of the water leg 23, and which is formed with a central annular flange 26 closing the leg extension and defining an opening 27 in axial alignment with the upper shell 18. Water or any other medium to be heated may be introduced through a line 28 opening tangentially to the water leg 23 about the flange 26, and the heated medium may be taken from the top of the chamber 21 through an opening (not shown).

Located in the upper portion of the chamber 21 just below the normal water level and in spaced relation between the shells 12 and 18 is an annular exhaust header 30 adapted to be connected to a stack (not shown). A plurality of vertical heating flues or passages 32 extend through the chamber 21, and open at their upper and lower ends respectively to the header 30 and the intermediate section 20 of the combustion chamber 2. These passages are defined by a plurality of coaxially spaced shells 33 intermediate the shells 50

12 and 18. It will be seen that the shells 12, 18 and 33 define alternate annular passages for the water or medium to be heated and the gases of combustion. The water passages are brought 5 into intercommunication at their ends by a plurality of connecting tubes 34 opening laterally through gas passages. The lower ends of the water passage, except for the water leg 23, are closed by annular walls which define the intermediate section 28 of the combustion chamber 2.

10 A heating element 42, adapted to supply hot water for domestic use, is positioned in the hottest zone of the water chamber 21.

15 The burner assembly 3 is mounted within a hood 44 on the top wall 11 of the housing 5. Opening at its upper end to the hood 44 is a vertical air duct 45 extending to the lower portion of the housing 5. The lower end of the duct 45 is open to the atmosphere, and is provided with 20 a weighted gate valve 46 normally open in response to natural draft, and adapted to close in the event of back pressure.

25 The burner assembly comprises a powdered fuel nozzle 47 positioned to discharge a mixture of fuel and primary air under pressure downwardly through a flanged opening 48 in the wall 11 centrally into the upper end of the combustion chamber 2. The opening 48 is substantially larger than the nozzle 47 to define an annular space for 30 the admission of secondary air from the hood 44. Secured on the wall 11 and partially overlying the opening 48 is a mounting bracket 49 for the nozzle 47. A fuel mixture supply line is connected to the nozzle 47, and consists of an elbow 35 51 with an enlarged end secured to the nozzle 47, a series of connected pipe sections 52, 53 and 54 within the hood 44, and a flexible tube 55 leading to the feeding apparatus 4.

40 The duct 55 is supplied with a mixture of comminuted fuel and air under pressure from the feeding mechanism 4. The mechanism generally comprises a centrifugal fan or blower 67, a fuel hopper 68, a fuel feeding member 69 for conveying fuel from the hopper into the inlet 45 passage of the blower for entrainment with the air passing therethrough, an agitator 70 in the hopper, and a common drive means for the blower, the feeding member and the agitator.

50 In its preferred form, the blower 67 (see Figs. 3 and 4) comprises two opposite side walls 71 and 72 defining a casing with a peripheral outlet 73 to which the duct 55 is connected, and a rotary propeller 74 mounted on a shaft 75 and consisting of a closed circular disk with peripherally spaced vanes 76 on opposite sides. The side wall 71 has a plurality of centrally located air inlet openings 77 under the control of a manually adjustable damper 78. The other side wall 72 is formed on the exterior with a radial horizontal duct 79 defining an inlet passage opening axially to the blower casing. To support the blower 67, the wall 72 is bolted to an upstanding flange 80 on one end of a bracket 81 adjustably mounted on a horizontal base plate 82. The propeller shaft 75 constitutes one shaft of an electric drive motor 83 also mounted on the bracket 81. A bolt 84 extending through the base plate 82 and an elongated slot 85 in the bracket 81 affords means for clamping these parts together, and when loosened permits adjustment of the bracket, the blower 67 and the motor 83, as a unit, longitudinally of the duct 79.

75 The hopper 68, in its preferred form (see Figs. 2 to 5), comprises an upright base section 86 circular at its upper end and tapered downwardly,

and a relatively large superstructure 87 mounted thereon. Preferably, the base section 86 is generally V-shaped in one vertical cross-section, and rounded at its closed lower end in the perpendicular cross-section, and comprises two flanged side walls 88 and 89 securely bolted together. The side wall 88 is formed integral with a mounting bracket 90 securely bolted to a bracket 91 on the base plate 82. The upper end portion of the superstructure 87 is cylindrical in form, and is 10 closed at the top by an end wall 92 having a central man hole cover 93 accessible from above the housing 5. The lower portion of the superstructure 87 is tapered conically, and merges into a circular neck portion 94 on the base section 86. 15

To support the hopper 68 and the other units of the feeding mechanism 4, vertical posts or standards 95 are connected at their upper ends to the superstructure 87, and horizontal tie bars 96 serve to connect the superstructure to the shell 20 12 of the heater 1.

25 Comminuted fuel may be introduced into the top of the hopper 68 through a pipe 97 adapted to be connected to a suitable source (not shown). Fuel is adapted to be delivered from the base section 86 of the hopper 68 through an elongated vertical opening or slot 98 between the marginal edges of the walls 88 and 89. The base section 86 is formed with a fuel entraining chamber or passage 99 in alignment with the duct 79, and in communication intermediate its ends with the delivery opening 98. One end of the entraining passage 99 may be connected to a suitable source of air, and preferably is connected to a line 100—100a. Secured in the other end of the entraining passage 99 is a connecting duct 101 which extends telescopically with a close sliding fit into the free outer end of the blower inlet passage 79. It will be seen that the telescoping relation of the passage 79 and the duct 101 permits adjustment 40 of the blower 67 with the bracket 81.

30 Fuel is delivered through the opening 98 by the feeding member 69 which preferably consists of a thin toothed sprocket or feed wheel or disc mounted on a horizontal shaft 102 in the bottom of the base section 86, and conforming closely to the curvature thereof. A portion of the periphery of the wheel 69 extends through the opening 98 into the passage 99. The passage 99 is generally elliptical in cross section with the major axis 35 generally vertical to receive a relatively large portion of the periphery of the feed disc 69 for a relatively small cross sectional flow area of the passage. Preferably, the wheel or disc 69 is rotatable on an axis parallel to and in substantially the same horizontal plane as the passage 99. The shaft 102 may be driven from any suitable source of power, such as the motor 83. Preferably, one end of the shaft 102 extends through a bearing 103 into a gear housing 104 integral with the exterior of the side wall 89. A worm wheel 105 fixed on the shaft 102 meshes with a worm 106 on a transverse shaft 107 journaled in and extending from the housing 104. A pulley 108 is secured to one end of the shaft 107, and is connected through a V-belt 109 to a pulley 110 on a second shaft 111 of the motor 83. Pulleys 110 of different sizes may be substituted to drive the feed wheel 69 at different speeds, and thereby vary the rate of fuel feed. 45

50 A guard 112 is provided in the base section 68 about the opening 98 to prevent the free passage of fuel thereto, and to prevent large foreign bodies or obstructions, such as nails, rocks or uncrushed lumps of coal, that may be present on occasion, 55

from entering and remaining between the sprocket teeth of the feed wheel 69. In the present instance, the guard 112 consists of two vertical contacting flanges projecting inwardly from the edge 5 margins of the walls 88 and 89 about the delivery opening 98. Formed in the inner vertical edge of the guard 112 is a deep groove 113 receiving the adjacent portion of the feed wheel 69, and 10 communicating intermediate its ends with the delivery opening 98. The grooved edge of the guard 112 extends substantially from the top of the feed wheel 69 and directly over the shaft 102 downwardly at an angle toward the edge of the base section 86. Of the groove 113, the root surface 15 conforms to and has a close fit with the periphery of the feed wheel 69, the sides closely embrace the opposite sides of the wheel, and the upper end defines a horizontal slot 114 through which the wheel 69 is adapted to carry fuel lodged in the interdental spaces between the teeth. The side 20 edges of the slot 114 extend tangentially across and are in shearing relation to the upper teeth of the wheel 69, and, upon rotation of the wheel in a clockwise direction as viewed in Fig. 5, act to 25 lift and remove any foreign bodies therefrom unless the latter are small enough to completely enter the interdental spaces and pass out with the fuel. In operation, fuel enters between the upper teeth of the wheel 69, and, as the teeth enter 30 the groove 113, is trapped therein until delivered through the opening 98 to the entraining passage 99.

The agitator 70 is mounted within the base section 86 of the hopper 68 to insure the movement 35 of fuel to the feed wheel 69. In its preferred form, the agitator 70 comprises a plurality of rotary members, such for example as two end members 115 and two intermediate members 116, mounted in axially spaced relation on a shaft 40 117 over the feed wheel 69 and parallel to the shaft 102. If the agitator 70 were not provided, the feed wheel 69 would tend to cut a groove 45 through the body of the fuel, and the fuel would tend to pack and bridge without entering the interdental tooth spaces.

The agitator is formed and located to prevent packing and bridging of the fuel adjacent the upper portion of the feed wheel 69, and to cause the fuel to move inwardly from the sides of the base section 86 toward the wheel and between the teeth. Thus, the intermediate members 116 closely 50 overlap with and are positioned respectively at opposite sides of the upper portion of the feed wheel 69, and are in the form of disks having closely spaced peripheral vanes 118. The vanes of each member 116 are alternately bent longitudinally to extend angularly in opposite directions out of the plane of the disk, and are all twisted laterally in the same direction so that upon rotation in a counter-clockwise direction as viewed in Fig. 5 they will impart an axial thrust 55 on the fuel toward the feed wheel 69. The end members 115 also have closely spaced peripheral vanes 119. In each instance, the vanes 119 are bent longitudinally at an angle toward the feed wheel 69, and are twisted laterally in the same direction to urge the fuel inwardly toward the wheel. By reason of the inward axial thrust exerted by the agitator and opposed rotation of the wheel 69 and the agitator 70, the spaces between the teeth are filled with fuel even though the wheel is comparatively thin.

The agitator shaft 117 is journaled in and extends through bearings 120 and 121 respectively on the side walls 88 and 89. One outer end of

the shaft 117 is connected through reduction gears 122 and 123 to the shaft 102 which extends out of the housing 104 through a bearing 124.

A flanged spacer ring 125 is interposed between the base section 86 and the neck portion 94 of the hopper 68 to space the superstructure 87 above the agitator 70. If it should be desired to empty the base section 86 without emptying the superstructure 87, a plate (not shown) may be inserted 5 between the neck portion 94 and the ring 125, 10 without interference with the agitator 70, to close the bottom of the superstructure.

The motor 83 serves to drive the blower 67, the feed wheel 69 and the agitator 70. The belt 109 may be suitably tensioned by adjusting the 15 bracket 82, this movement being permitted by the telescoping relationship of the duct 79 and the duct 101. The agitator 70 loosens the fuel in the hopper 68, and causes it to move toward the feed wheel 69 and into the tooth spaces. Packing and 20 bridging of the comminuted fuel is thus effectively prevented. In the rotation of the feed wheel 69, the interdental spaces between the teeth become filled with fuel, and carry the trapped fuel through the groove 113 and the delivery opening 98 25 into the passage 99. Here, the fuel is entrained in atmospheric air drawn in by the suction of the blower 67 from the hopper 68.

It will be seen that the blower 67 takes in two 30 separate streams of air, one through the passage 79 laden with entrained fuel, and the other directly from the atmosphere through the openings 77. Hence, the blower 67 may be considered functionally as two separate blowers. The total 35 volume of air entering the blower 67 constitutes the primary air of combustion. The velocity of the air for entraining the fuel may be adjusted by means of a damper 126 transversely slidable in the passage 99 toward and from the periphery of the feed wheel 69. The volume of air entering the inlet openings 77 may also be adjusted by the damper 78, this adjustment serving mainly to vary the richness of the primary fuel-air mixture.

I claim as my invention:

1. In a powdered fuel combustion apparatus, a feeding mechanism comprising, in combination, a vertical hopper having a base section formed with a horizontal air-flow entraining passage and a vertical delivery slot communicating therewith, a peripherally toothed feed disc rotatable in said section on an axis in the same horizontal plane as said passage and projecting over a portion of its periphery through said slot into said passage, means for causing flow of air through said passage to entrain the fuel delivered thereto by said feed disc, and means for driving said feed disc, said passage being generally elliptical in cross section with the major axis generally vertical at said slot to receive a relatively large portion of the periphery of said disc for a relatively small cross sectional area of said passage.

2. In a powdered fuel combustion apparatus, a feeding mechanism comprising, in combination, a blower having a suction inlet passage, a hopper having a base section generally V-shaped in form and with a generally vertical elongated delivery slot in one edge opening to said passage, a peripherally toothed thin feed disc rotatable in said section in freely spaced relation to the walls thereof and projecting over a portion of its periphery through said slot into said passage, and a guard projecting from about said slot into said section and closely overlapping the sides of said disc to close the ends and sides of the tooth spaces.

of said disc as the teeth approach and leave said slot, and means for driving said blower and said disc.

3. In a powdered fuel combustion apparatus, a feeding mechanism comprising, in combination, means defining an air-flow passage, a fuel hopper having a delivery outlet opening to said passage, a peripherally toothed rotary feeding member in said hopper for discharging fuel through said outlet into said passage, a guard within said hopper about said outlet and coacting with said member to eject large foreign obstructions substantially radially from between the teeth on said member as said teeth approach said outlet, and means for driving said member.

4. In a powdered fuel combustion apparatus, a feeding mechanism comprising, in combination, means defining an air-flow passage, a fuel hopper having a delivery outlet opening to said passage, a rotary toothed feed wheel in said hopper and projecting through said outlet into said passage, a guard about said outlet and formed with a closely fitting notch receiving the adjacent portion of said feed wheel, one end of said notch defining shearing edges extending tangentially across the approaching teeth of said wheel to lift foreign obstructions therefrom, and means for rotating said wheel.

5. In a powdered fuel combustion apparatus, a feeding mechanism comprising, in combination, pressure discharge means having an air-flow passage, a hopper having a delivery outlet opening to said passage, a rotary peripherally toothed feeding disc mounted for rotation on an axis generally parallel to said passage for delivering fuel through said outlet into said passage for entrainment by the air flowing through and past the tooth spaces of said disc in a direction generally parallel to said axis, an agitator comprising a plurality of rotary vane members axially offset from said disc and overlapping with and disposed respectively at opposite sides of a portion of the toothed periphery of said feeding disc, said vane members having inclined faces to advance fuel axially and peripherally into the spaces between the teeth on said disc, and means for driving said disc and members.

6. In a powdered fuel combustion apparatus, a feeding mechanism comprising, in combination, pressure discharge means having an air-flow passage, a hopper having a delivery outlet opening to said passage, a vertical rotary peripherally toothed feeding disc in said hopper for delivering fuel through said outlet into said passage for entrainment by the air flowing therethrough, the axis of said disc being generally parallel to the direction of flow of air in said passage across said outlet, two rotary agitator disks axially offset from said feeding disc and closely overlapping opposite sides of the upper toothed portion of said feeding disc, each disk having a plurality of peripheral vanes twisted laterally to advance fuel axially toward said feeding disc and into the tooth spaces thereof and alternately inclined longitudinally in opposite directions, and means for driving said feeding disc and said disks.

7. In a powdered fuel combustion apparatus, a feeding mechanism comprising, in combination, pressure discharge means having an air-flow passage, a hopper having a delivery outlet opening to said passage, a vertical rotary peripherally toothed feeding disc disposed in freely spaced relation in said hopper for delivering fuel through said outlet into said passage for entrainment by

the air flowing therethrough, the axis of said disc being generally parallel to the direction of flow of air in said passage across said outlet, two rotary agitator disks axially offset from said feeding disc and closely overlapping opposite sides of the upper toothed portion of said feeding disc, each agitator disk having a plurality of peripheral vanes twisted laterally to advance fuel axially toward said feeding disc and into the tooth spaces and alternately inclined longitudinally in opposite directions, two additional rotary agitator members respectively at opposite sides of said agitator disks and having peripheral vanes twisted laterally to advance fuel toward said feeding disc and inclined longitudinally toward said agitator disks, a shaft for supporting said agitator disks and members in coaxial relation, and means for driving said feeding disc and said shaft.

8. In a powdered fuel combustion apparatus, a fuel feeding mechanism comprising, in combination, a vertical hopper base having two connected opposite side casing members with contacting externally flanged marginal edges to define a space substantially closed excepting at the top and generally V-shaped in a transverse vertical cross-section and rounded at the lower end in a perpendicular vertical cross-section, means on said base defining a horizontal transverse flattened air-flow passage, said edges along a portion of one vertical margin of said base being spaced to define a narrow vertical slot establishing communication between said space and said passage, and being formed with internal contacting marginal flanges extending substantially to the center of said space, said flanges having free vertically inclined margins and free upper horizontal margins and being recessed in their adjacent sides to define a narrow vertical groove with an arcuate root, a thin peripherally toothed feed wheel mounted in said base for rotation on an axis in the same horizontal plane as said passage and projecting over a substantial portion of its periphery with a close running fit into said groove closely to said root and through said slot into said passage, said upper margins of said flanges extending at an angle across the sides of the uppermost teeth of said wheel at the point where said teeth enter said groove, and drive means for rotating said wheel in a direction to move said teeth across said upper margins into said groove.

9. In a powdered fuel combustion apparatus, a fuel feeding mechanism comprising, in combination, a vertical hopper base having two connected opposite side casing members with contacting marginal edges to define a space substantially closed excepting at the top and generally V-shaped in a transverse vertical section, means on said base defining a horizontal transverse air-flow passage, said edges along a portion of one vertical margin of said base being spaced to define a narrow vertical slot establishing communication between said space and said passage, and being formed with internal contacting marginal flanges extending substantially to the center of said space, said flanges having free upper margins and being recessed in their adjacent sides to define a narrow vertical groove with an arcuate root, a thin peripherally toothed feed wheel mounted for rotation in said base section and projecting over a substantial portion of its periphery with a close running fit into said groove closely to said root and through said slot into said passage, said upper margins of said flanges extending at an angle across the sides of the uppermost teeth of said wheel at the point where said

teeth enter said groove, and drive means for rotating said wheel in a direction to move said teeth across said upper margins into said groove.

10. In a powdered fuel combustion apparatus, 5 a feeding mechanism comprising, in combination, a fuel hopper having an outlet opening, air supply means having an air-flow passage extending transversely of said hopper and communicating laterally with said opening, a feed wheel mounted 10 for rotation in said hopper and projecting over a portion of its periphery through said opening to one side of said passage, a slide valve extending into the other side of said passage in the plane of said wheel and having an arcuate inner edge 15 conforming to the curvature of said wheel and adjustable toward and from the periphery of said wheel to control the effective flow area of said passage, and means for driving said wheel.
11. In a powdered fuel combustion apparatus, a 20 feeding mechanism comprising, in combination, a fuel hopper having an outlet opening, air supply means having an air-flow passage communicating laterally with said opening, a feed wheel mounted for rotation in said hopper and projecting 25 over a portion of its periphery through said opening into one side of said passage, a slide valve extending into the other side of said passage and being adjustable in the plane of said wheel toward and from the periphery of said wheel to 30 control the effective flow area of said passage, and means for driving said wheel.

12. In a powdered fuel combustion apparatus, a feeding mechanism comprising, in combination, a centrifugal blower having an axial atmospheric air inlet at one side and having an air induction passage opening axially into the other side, an adjustable valve for said inlet, a fuel hopper having an outlet communicating laterally with said passage, a peripherally toothed feed 35 wheel mounted for rotation in said hopper and projecting over a portion of its periphery through said outlet to permit the entrainment of fuel from between the teeth in the air flowing through said passage, and adjustable valve means co- 40 acting with said wheel for controlling the flow of air through said passage.

13. In a powdered fuel combustion apparatus, a feeding mechanism comprising, in combination, means defining an air-flow passage, a fuel hopper having an elongated narrow delivery outlet to said passage, a guard projecting into said hopper and formed in its free edge with a groove opening intermediate its ends to said outlet, a peripherally toothed feed wheel mounted for 45 rotation in said hopper and projecting over a portion of its periphery with a close side fit through said groove into said outlet, the root of

said groove at opposite ends of said outlet being arcuate and conforming closely to the periphery of said wheel.

14. In a powdered fuel combustion apparatus, 5 a feeding mechanism comprising, in combination, means defining an air-flow passage, a fuel hopper having an elongated narrow delivery outlet to said passage, a guard projecting into said hopper and formed in its free edge with a groove opening intermediate its ends to said outlet, a 10 peripherally toothed feed wheel mounted for rotation in said hopper and projecting over a portion of its periphery with a close side fit through said groove into said outlet, the root of said groove being arcuate and conforming closely 15 to the periphery of said wheel, the inlet end of said groove defining edges in shearing relation with the sides of the teeth of said wheel, and adapted to lift obstructions therefrom.

15. In a powdered fuel combustion apparatus, 20 a feeding mechanism comprising, in combination, a hopper base having an outlet and open at the top, a spacer ring removably secured to the top of said base, a hopper super-structure mounted on and removably secured to the top of 25 said ring, a peripherally toothed feed wheel mounted for rotation on a horizontal axis in said base for discharging fuel through said outlet, and a rotary agitator mounted in said base over said feed wheel and in overlapping relation with 30 the sides of said feed wheel, said agitator projecting upwardly into said spacer ring and terminating below said super-structure.

16. In a powdered fuel combustion apparatus, 35 a fuel feeding mechanism comprising, in combination, means defining an air-flow passage, a fuel hopper having a delivery outlet to said passage, a peripherally toothed feed wheel mounted for rotation on a horizontal axis in said hopper for 40 delivering fuel to said outlet for entrainment by the air flowing through said passage, said axis being generally parallel to said passage at said outlet, a shaft for supporting said feed wheel extending into said hopper, a parallel shaft extending into said hopper directly above said first 45 mentioned shaft, spaced rotary agitators mounted on said last mentioned shaft respectively at opposite sides of said feed wheel, said agitators having inclined faces adapted to direct fuel axially toward the upper portion of the periphery of said feed wheel and into the tooth spaces thereof, means including a speed reduction gearing for 50 driving said first mentioned shaft, and a speed reduction gearing connecting said shafts to drive said shafts in opposite directions of rotation in 55 continuous uniformly timed relation.

AUBREY J. GRINDLE.
